Specification for Design.

Patented Feb. 25, 1913.

Application filed October 4, 1911. Serial No. 652,856. Term of patent 14 years.

To all whom it may concern:

Be it known that I, JOSEPH T. ROFFY, a subject of the Emperor of Austria-Hungary, residing in Chicago, in the county of Cook and State of Illinois, have invented a new, original, and ornamental Design for Sign-Projectors, of which the following is a specification, reference being had to the accompanying drawing, forming a part thereof.

The figure of the drawing is a perspective view showing the design of the article.

I claim:

The ornamental design for a sign projector as shown.

JOSEPH T. ROFFY.
